Emory Osgood

UNITED STATES PATENT OFFICE.

ENOCH OSGOOD, OF BOSTON, MASSACHUSETTS.

IMPROVED BALANCE PRESSURE-REGULATOR FOR STEAM, WATER, OR GAS.

Specification forming part of Letters Patent No. 35,104, dated April 29, 1862.

To all whom it may concern:

Be it known that I, ENOCH Osgood, of Boston, county of Suffolk, and State of Massachusetts, have invented a new and useful Improved Regulator for Regulating and Balancing the Pressure of Steam, Water, Air, or Gas, as desired; and I do hereby declare the following to be a full and exact description thereof, reference being had to the accompanying drawings and letters of reference marked thereon.

Figure 1 is a vertical sectional view of my invention, showing all its parts and their operation; Fig. 2, a longitudinal elevation; Figs. 3 3, couplings; Figs. 4 4, valve and valve-seat.

I do not claim the arrangement made with a large iron cap and a very small beveled valve connected together by a stiff rod, the cap set in mercury and weighted to open the valve to let the gas pass into the regulator through the valve instead of out through it for use, for that has been tried and found useless.

The nature of my invention consists in the application and combination of a valve and a diaphragm a little larger than the valve or their equivalent arranged and connected together to operate against each other to hold and balance any pressure that may come against them, the gas coming in between them and out through the valve into the chamber below it for use, as shown in the drawings.

The following is a description and illustration of my invention.

A represent a tube, box, or pipe for the steam, water, air, or gas to pass through for use; B, outlet on the upper side and end covered with a flexible diaphragm, D. At the other end, on the under side, is a valve, E, with sharp square edges, and hung by its pintle F on a hook on the lower end of wire G, the end of said wire passing up through the diaphragm and a dish that is on it, and fastened to them by a nut above and below them, screwed to them gas-tight, connecting the valve and diaphragm together. For steam, piston-heads may be used. The diaphragm, being somewhat larger than the valve E, gives it power to close it. Thus when the gas passes into the regulator between the valve and diaphragm, the valve

will be closed, because more surface is exposed to the pressure of the gas by the increased size of the diaphragm over that of the valve. By putting weights into the dish attached to the diaphragm I can, more or less, equalize the excess of pressure on the diaphragm, so that the valve will open as much as desired and allow the gas to pass out through it into the chamber below it for use, and the pressure in the chamber below the valve from which the gas is used is regulated as desired by the amount of weight placed in the pan on the diaphragm, the weights balancing to the degree required the excess of pressure gained upon the diaphragm by its increased size over the valve and regulating the pressure in the chamber below the valve without regard to the amount of pressure in the chamber between the valve and the diaphragm, whether the pressure be one or ten pounds. If the gas is withdrawn from the chamber under the valve, the power of the weights on the diaphragm will be exerted to open the valve until a sufficient amount of gas can pass through to again establish the original equilibrium, and there being no friction the action is immediate and steady and the result certain. When the pressure is not being removed from the chamber under the valve, the pressure between the valve and diaphragm and below the valve will of course become the same, and the excess of size in the diaphragm will cause the valve to close, thus making a self-regulator of the pressure, and saving from twenty-five to thirty-five per cent of gas with the same light.

By this regulator water for running factories and mills can be regulated as easily as steam is now regulated for the same or any other purpose.

H is a bar across the valve-seat to guide the valve; I, valve-seat, beveled; J, screw through which to remove the coal-tar or any other impurities or obstruction.

I do not claim the large iron cap set in mercury, weighted and connected by a stiff rod to a small valve to open it to let the gas pass into the regulator through the valve instead of out through for use, for that is useless; but

What I do claim, and desire to secure by Letters Patent, is—

The combination of a valve and a diaphragm

enough larger than the valve to give it any desired power over it wanted to close it to hold and balance any pressure that may come in between them, to be weighted out by weights on the diaphragm to give the desired pressure wanted in the chamber below the valve for use, constructed and connected together to

operate against each other, substantially as and for the purpose herein described.

ENOCH OSGOOD.
